Primary Examiner — Karen S Acker*Assistant Examiner* — Katrina Gonzalez(74) Attorney, Agent, or Firm — Banner & Witcoff, Ltd.(57) CLAIM

The ornamental design for a dress, as shown and described.

DESCRIPTION

FIG. 1 is a front right perspective view of a dress showing my new design in an in-use configuration;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The dot-dash-dot broken lines immediately adjacent to the shaded areas depict the boundaries of the claim and form no part thereof. The unshaded regions, demarcated by evenly spaced broken lines, depict portions of the dress that form no part of the claimed design.
